Primary Examiner — Ian Simmons*Assistant Examiner* — Keith Frank*(74) Attorney, Agent, or Firm* — Polson Intellectual Property Law, PC; Margaret Polson(57) **CLAIM**

The ornamental design for a bottle, as shown and described.

DESCRIPTION

FIG. 1 is a front side elevation view of my new design for a bottle.

FIG. 2 is a side elevation view of the right and left sides, which are mirror images, of FIG. 1.

FIG. 3 is a back side elevation view of FIG. 1; and, FIG. 4 is a bottom plan view of FIG. 1.

The broken lines in the drawings illustrate the portions of the bottle that form no part of the claimed design.
